FLUID OPERATED PRESS

George Couri, Astoria, N. Y.

Original application December 11, 1947, Serial No. 791,077. Divided and this application December 8, 1948, Serial No. 64,111

6 Claims. (Cl. 175—335)

1

My invention relates to an improvement in fluid-operated presses such as garment presses for example, and has for one of its objects the simplification of the controlling mechanism of such presses, thereby to reduce initial cost as well as maintenance expenses.

Another object of my invention is an improvement in the fluid-control valve mechanism whereby valve failure and failure of the controlling mechanism therefor are substantially completely eliminated.

In addition to the foregoing, my invention provides controlling mechanism for controlling a press, when a single press is operated, or for controlling a plurality of presses which is of such a nature that danger of injury to the operator is eliminated, means being provided whereby the operator is required to employ both hands in closing the press until the press has closed sufficiently to a point where danger to the operator has passed.

My invention also provides solenoid-operated valve mechanism, constructed and arranged so that burning out of the solenoid due to a variation in the valve closure is prevented, and hence extreme accuracy in setting the solenoid and the valve is unnecessary, my construction permitting of some movement of the core of the solenoid following seating of the valve, so that I am always assured of a fully operated solenoid.

These and other objects of my invention will be brought out fully in the description which follows.

In the drawings wherein my invention in several forms has been illustrated:

Fig. 1 is a fragmentary part sectional elevational view showing the valve mechanism for a press;

Fig. 2 is a wiring diagram for a single press embodying my invention, in which the holding and maintaining circuits comprise a double pole relay;

Fig. 3 is a wiring diagram for two presses arranged in tandem; and

Fig. 4 is a wiring diagram for a single press employing a single pole relay for the holding and maintaining circuits.

Referring to the drawings in detail, and first of all to Figs. 1 and 2 thereof:

As is well known to those skilled in the art, fluid-operated garment presses conventionally comprise a lower stationary buck upon which the work to be pressed is laid, and an upper buck which is lowered by pressure fluid and raised by a spring. Because this construction is well

2

known, I have only illustrated enough of this structure in Fig. 1 to make the same understandable.

In Fig. 1 of the drawing, 2 designates the actuating arm for the upper buck of a garment press. This arm is pivoted at 4, and is actuated about the pivot in a direction to close the press, that is, to lower the upper buck by a pressure-fluid-operated piston 6, pivoted to the outer end of 10 the lever 2, while one end of the piston cylinder 8 for this piston is pivoted to the press frame or bed as illustrated at 10.

The pressure-fluid supply line is designated 12. The body or housing for the valves controlling 15 the pressure-fluid is designated 14. This housing or body is provided with inlet port 16 controlled by inlet valve 18 and with an outlet or exhaust port 20 controlled by exhaust valve 22. The inlet and exhaust valves close and open oppositely, that is, when one closes or seats, the other opens, and are connected to each other by a rod 24. The valves may take the form of discs which are merely slipped over the ends of the rod 24, which simplifies assembly and replacement. The 25 inlet valve 18 is spring-loaded, the spring, which is designated 26, holding the valve closed when the press is open.

The pressure-fluid line 12 is connected to the valve body to the rear of inlet valve 18, and 30 when this valve is open, pressure-fluid can pass to the piston cylinder 8 through hose or pipe connection 13.

28 designates a pin or plunger extending into the end of the valve body or housing 14 and 35 projecting therefrom. This pin or plunger is in effect a stem for the exhaust valve 22 and in a way for the inlet valve 18. It will be apparent from Fig. 1 that if the plunger 28 be pushed inwardly of the valve body the exhaust valve 22 40 will be seated and the inlet valve 18 unseated.

The plunger 28 is actuated inwardly of the valve body by a solenoid 30. The control circuits for this solenoid will be described presently.

The valve mechanism and the solenoid 30 may 45 conveniently be mounted in a control box 32. Pivoted to the wall of this box or to some other fixed point is a short arm 34, to the free end of which a link 36 is pivotally attached. The free end of the arm 34 lies beneath and in contact with the outer end of the valve-operating plunger 28, as will be seen from Fig. 1. The link 36 is pivotally attached to arm 38 of a bell crank lever, the other arm 40 of this bell crank being connected by a slot and pin connection to the 50 plunger 42 of the solenoid 30.

The bell crank lever has a floating pivot 44. From Fig. 1 it will be seen that 45 designates a fixed block which may be secured to the wall of box 32 or otherwise rigidly positioned, this block being located some distance directly below the bell crank pivot 44. Extending upwardly with a loose fit through the block 46 is a pin 48. The pin is threaded into a block 49 pivoted to the bell crank. Above the block 46 the pin 48 carries coil spring 50, a nut 52, for adjusting the tension of the spring and lock nut 54.

The lower end of the adjusting pin 48 carries a nut 56 by which the effective length of the pin may be varied, and a lock nut 58.

This arrangement, it will be apparent, provides a floating pivot for the bell crank.

In setting up this equipment it is necessary merely to adjust the setting of the pin 48 in the block 46 until, when the solenoid 30 is energized to move the valve plunger 28 upwardly the exhaust valve 22 will be closed. With the exhaust valve seated, the plunger 42 of the solenoid 30 should be at its extreme inner position and the nuts 56 and 58 should be manipulated until this is the case. While the parts initially can properly be set, wear on the valve 22 will throw this adjustment out slightly so that while the valve seats properly at first it may not close fully when worn. For this reason I provide the floating pivot for the bell crank and in originally setting up the equipment I provide for seating of the valve slightly in advance of full movement of the plunger 42. Consequently, in operation, when the solenoid 30 is energized the plunger 28 will be actuated fully to close the valve 22 slightly in advance of full movement of the solenoid plunger, this slight further movement of the plunger being permitted by the provision of the loose fit of pin 48 in block 46 which allows slight displacement of bell crank pivot 44 sufficient to permit the solenoid plunger to complete its travel after the valve 22 has fully seated.

This arrangement, therefore, provides for seating of valve 22 and full movement of the solenoid plunger 42 at all times, thereby eliminating the possibility of leak past the valve 22 and burning out of the solenoid.

Referring now to the wiring diagram of Fig. 2:

This figure of the drawing illustrates one method of wiring when my equipment is installed on a single press. 60 and 62 designate two manually operated switches with which the press is equipped. These switches, which are usually simple push button switches, are so placed as to require the operator to employ both hands in closing them. They are employed in the initial closing operation of the press, but when the press is idle they stand in open position.

64 is a release switch, normally closed, this switch being employed to open the press.

66 is a limit switch controlled by a movable part of the press, this switch, which may be made adjustable, taking over the control of the press when the press buck reaches a certain position in its closing operation.

68 is a double pole relay which is operative only when switch 66 is closed and provides for maintaining a circuit closed for the solenoid 30.

In the wiring diagram the switches have been illustrated in the position they occupy when the press is idle. Assuming now that the press is to be operated: The operator closes the switches 60 and 62 which closes a circuit to the solenoid 30 by way of conductor 70 which is connected to 75

suitable electric supply source through release switch 64 which is normally closed; through manual switch 62, conductor 72, coil of the solenoid 30, conductor 74 and manual switch 60, conductor 76 to the other side of the line. At this time the coil of relay 68 is not energized.

Upon reference to Fig. 1 it will be seen that with solenoid 30 energized, exhaust valve 22 will be closed and supply valve 18 opened so that pressure fluid can flow to piston cylinder 8 to actuate the arm 2 in a direction to move the upper buck of the press toward closed position. Because the switches 60 and 62 are in the closing circuit of the press the operator's hands are both occupied so that danger of the operator placing his hand beneath the buck at this stage is eliminated. Should the operator release either or both of the switches 60 and 62, then the circuit to the solenoid 30 will be opened immediately and spring 26 will immediately force the valves to the position illustrated in Fig. 1 to exhaust the pressure fluid so that the press will open under the action of the opening spring 77.

When the press has reached a predetermined position in its closing movement, the switch 66 will be closed, one side of this switch, as above pointed out, being attached to a moving part of the press. Closure of this switch 66 will close a circuit to the relay 68 by way of conductor 70, release switch 64, manual switch 62, conductors 72, 78, coil of relay 68, conductor 80, switch 66, conductors 82 and 76 to the other side of the line.

The relay 68 being energized, the same will close its contacts to establish a holding circuit for this relay independently of the switches 60 and 62, so that the latter can be released. This holding circuit is by way of conductor 70, release switch 64, conductor 84, one side of the relay 68, conductor 86, winding of the relay, conductor 88, switch 66, conductors 82 and 76 to the other side of the line. The relay when closed also maintains a circuit to the solenoid 30 by way of conductor 70, release switch 64, conductor 84, one side of the relay 68, conductors 86, 78, solenoid 30, conductors 74, 88, the other side of relay 68, conductor 80, release switch 66, conductors 82 and 76 to the other side of the line.

From the foregoing it will be apparent that during the first part of press operation the manual switches 60 and 62 must be closed to energize the solenoid 30 thereby to open supply valve to the press and close the exhaust valve. During this closing movement, release of either or both of the switches 60 and 62 will effect de-energization of solenoid 30 and the exhaust valve 22 will open to allow the press to open. Of course during this same period, opening of release switch 64 will open the circuit of solenoid 30 permitting the press to open. Upon closure of the press sufficiently to close switch 66, the relay 68 is energized to close a holding circuit for the relay, the relay also holding closed the circuit for solenoid 30 with the manual switches 60 and 62 released. The press will remain closed under pressure until release switch 64 is opened, whereupon the press will open under the action of its opening spring. The operator therefore must hold the switches 60 and 62 closed until the press has closed sufficiently to close the switch 66 to energize the winding of the relay 68.

It will be apparent also that the operator must hold the switches 60 and 62 closed until the press has closed sufficiently to close the switch 66, and that thereafter the switches 60 and 62 may be released and allowed to stand open, the

press closing with full pressure and remaining closed until the release switch 64 is opened.

It will be apparent also that because the holding circuit for the relay 68 is through one side of the relay and is closed only when the relay is closed, and the maintaining circuit for the solenoid 30 is through the other side of the relay, should the release switch 64 be opened unintentionally, the windings of the relay 68 and solenoid 30 will be opened, even though the switch 66 is closed at that instant, and the circuit of solenoid 30 will not close again simply by closing release switch 64, but closure of the manual switches 60 and 62 is required.

In the diagram of Fig. 3 I have illustrated two presses connected in tandem.

Each press is equipped with a pair of manual switches corresponding with the switches 60 and 62 of Fig. 2 and with a release switch corresponding to the release switch 64 of Fig. 2. In this diagram each press is equipped with a switch corresponding to the switch 66 of Fig. 2.

In addition, each press is equipped with a tandem switch whereby an operator may stand at one machine and open another although the machines may be widely separated.

To avoid confusion and make for clarity of description, an entirely new set of reference characters will be employed on the diagram of Fig. 3.

In this diagram I have illustrated two presses designated #1 and #2.

Press #1 is equipped with two manually operated switches 90 and 92 corresponding to the manually operated switches 60 and 62 of Fig. 2; with release switch 94 corresponding to release switch 64 of Fig. 2; with a press-operated or limit switch 96 corresponding to switch 66 of Fig. 2, and with a tandem-switch 98.

This press is equipped with relay 68 and with solenoid 30, counterparts of relay 68 and solenoid 30 of Fig. 2.

Press #2 is equipped with two manually operated switches 100 and 102 corresponding with switches 60 and 62 of Fig. 2; with release switch 104 corresponding to release switch 64 of Fig. 2; with a press-operated or limit switch 106 corresponding to switch 66 of Fig. 2, and with a tandem-switch 108.

This #2 press is equipped with relay 68 and with solenoid 30, counterparts of relay 68 and solenoid 30 of Fig. 2.

Both presses have been illustrated in open position.

Assuming that #1 press is to be closed:

Switches 90 and 92 are closed to close a circuit to solenoid 30 and start the press toward closing position. The solenoid circuit is by way of conductors 110, 112, switch 90, conductors 114, 116, solenoid 30, conductor 118, switch 92, release switch 94, tandem-switch 108, which is on #2 press, conductors 120 and 122 to the other side of the line. When the press has closed sufficiently to close the press-operated switch 96, a circuit will be closed to relay 68 to close a circuit to solenoid 30 of #1 machine, this circuit including the switch 96. The relay circuit may be traced from one side of the line, conductors 110, 112, 121, press-operated switch 96, conductor 123, relay 68, conductors 124, 118, switches 92, 94, 108, conductor 120 to the other side of the line. The relay 68 now closes to establish a holding circuit for the relay and a maintaining circuit for the solenoid 30. The holding circuit for the relay may be traced from one side of the line,

conductors 110, 112, 121, press-operated switch 96, conductor 123, one side of relay 68, conductor 126, conductor 128, switches 94 and 108 to 122. The maintaining circuit for the solenoid 30 may be traced by way of conductors 110, 112, 121, switch 96, conductor 123, across one side of relay 68, conductors 130, 116, coil of solenoid 30, conductors 124, 126, 128, switches 94, 108, conductors 120, 122 to the other side of the line. Inasmuch as neither of these circuits includes the manual switches 90 and 92, it will be apparent that they may be left open and the press will close and remain closed.

To open #1 press it is merely necessary to open release switch 94 on the machine or to open tandem switch 108 on #2 machine. Both of these switches are in series with the coil of relay 68 so that the coil will be de-energized upon opening either switch and inasmuch as the relay must be closed in order that solenoid 30 will remain energized when manual switches 90 and 92 are released, it will be apparent that the press will open, and cannot be closed again except by closing the switches 90 and 92. In other words, the cycle traced must be repeated.

Referring to #2 machine, it will be seen upon reference to the drawing, that when manual switches 100 and 102 are closed, a circuit will be closed to the solenoid 30 of this machine, from one side of the line; conductors 110, 132, switch 106, conductors 134, 136, coil of solenoid 30, conductor 138, manual switch 102, release switch 104, conductor 140, tandem switch 98 on #1 machine, conductors 142, 122 to the other side of the line. The press will begin its closing movement and when the upper buck reaches a position where press-operated switch 106 is closed, a circuit will be closed to the coil of relay 68 of #2 machine. This circuit may be traced by way of conductors 110, 132, 144, switch 106, conductor 146, coil of relay 68, conductors 148, 138, manual switch 102, release switch 104 of #2 machine, conductor 140, tandem switch 98 of #1 machine, conductors 142, 122 to the other side of the line. Closure of relay 68 establishes a holding circuit for the relay and a maintaining circuit for the coil of solenoid 30 of #2 machine. The holding circuit may be traced by way of conductors 110, 132, 144, switch 106, conductor 146, coil of relay 68, conductor 150, one side of the closed relay, conductor 152, release switch 104 of #2 machine, conductor 140, tandem switch 98 on #1 machine, conductors 142, 122 to the other side of the line. The maintaining circuit for the coil of solenoid 30 may be traced from conductor 146, one side of relay 68, conductor 136, coil of the solenoid 30, conductors 148, 150, the other side of relay 68, conductor 152, release switch 104, conductor 140, tandem switch 98 of #1 machine, conductors 142, 122 to the other side of the line. Neither of these circuits includes the manual switches 100 and 102 so they may be released.

In the wiring diagram of Fig. 4 I illustrate a construction very similar to Fig. 2, except that that relay for the holding and maintaining circuits is a single pole relay instead of a double pole.

In this diagram 64 is the release switch, 62 and 60 the manually operated switches for initiating closure of the press, 66 is the press-operated limit switch which closes when the press has reached a pre-determined position in its closing movement; and 30 is the valve-controlling solenoid.

These parts all correspond to similarly designated parts in Fig. 2.

168 designates a single pole relay which has been substituted for the double pole relay 68 of Fig. 2.

To initiate closing of the press, the manual switches 62 and 60 are closed, which closes a circuit to the coil of solenoid 38. This circuit may be traced as follows: Conductor 10 connected to one side of an electric power line, release switch 64, which is normally closed, switches 62 and 60, conductors 170, 172, coil of solenoid 38, conductors 174 and 176 to the other side of the line.

Energization of solenoid 38 will of course effect opening of the fluid supply valve and the closure of the exhaust valve of the press as above explained to initiate the closing movement of the press.

At this time it will be seen from the drawing no current can flow through the relay 168 and the same remains open.

When the press reaches a predetermined position in its closing movement it will close the switch 66. A circuit is then established for the relay 168. This circuit may be traced from conductor 178, by way of conductor 178, through the coil of relay 168, switch 66, conductor 178 to the other side of the line. At the same time with the manual switches 62 and 60 still closed the solenoid 38 will be receiving current.

The instant that relay 168 functions, the switches 62 and 60 may be released, because the relay circuit will be held closed, the holding circuit being by way of conductor 78, release switch 64, conductor 180, across the relay, through the coil of the relay; switch 68, conductor 176 to the other side of the line. The coil of solenoid 38 is maintained energized. The maintaining circuit may be traced by way of conductor 78, release switch 64, conductor 198, across the relay, conductors 178, 172, coil of solenoid 38, conductors 174 and 176 to the other side of the line.

It will be apparent from the foregoing that in the three arrangements illustrated in Figs. 2, 3 and 4, the closing of the manually operated switches merely effects energization of the coil of the solenoid which operates the fluid valves; that when the press reaches a position in its closing movement where the press-operated switch is closed then a relay is closed, the closure of which establishes a holding circuit for the relay and a maintaining circuit for the valve solenoid so that the press will continue its closing movement, the manually operated switches may be released, and the press will move to full closed position and remain closed until a release switch is opened.

It is to be noted also in this connection that with the press closed, opening of the release switch, even though this is but a momentary opening, will de-energize the relay to open the circuit of the valve solenoid to start the opening cycle, and even though the release switch is instantly closed again, a circuit cannot be re-established to the valve solenoid except by operation of the manually operated switches.

It is to be noted in connection with the tandem diagram of Fig. 3, press #1 may be opened or its opening cycle initiated by opening the tandem switch 198 on press #1, and that press #2 may be opened, or its opening cycle initiated by opening tandem switch 98 on #1 machine. Of course it will be appreciated that #1 machine may be opened at the machine by simply opening release switch 94 which is on #1 machine

and that #2 machine may be opened at the machine by opening release switch 198 on #2 machine.

It is to be understood that changes may be made in the details of construction and arrangement of parts hereinabove described within the purview of my invention.

This application is a division of my co-pending application, Serial No. 791,077, filed December 11, 1947, Fluid-Operated Press.

What I claim is:

1. In a control for electrically controlled fluid-operated presses the combination of an electric circuit for initiating closure of the press, a manual switch for closing said circuit, a solenoid energized by closure of said electric circuit, a second switch adapted to be closed a predetermined time after energization of said solenoid, a relay whose circuit is completed upon the closing of said second switch, a holding circuit for said relay which is completed upon closure of said relay, and a maintaining circuit for the solenoid which is completed upon the said closure of the relay, said holding circuit and maintaining circuit remaining closed after said manual switch has been opened.

2. In a control for electrically controlled fluid-operated presses, the combination of a manually closed circuit for initiating closure of the press, 30 a solenoid, said solenoid initially being in said manually closed circuit, a switch which closes a predetermined time after the closure of the manual switch, a relay, the circuit for which is completed by closure of the second mentioned switch, a holding circuit for said relay completed by the said energization of the relay, and a maintaining circuit for said solenoid closed by the establishment of the relay circuit.

3. In a control for electrically controlled fluid-operated presses, the combination of a pair of manually operated switches, a solenoid, the circuit of said solenoid initially being established by closure of said manually operated switches, a second switch adapted to be closed a predetermined time after the establishment of the solenoid circuit, a relay, the circuit for which is established upon the closure of said second switch a holding circuit for said relay, separate from the solenoid circuit, said relay holding circuit being established by establishment of the relay circuit, and a maintaining circuit for the solenoid separate from the first-mentioned solenoid circuit, said maintaining circuit being established by establishment of the relay circuit.

4. In a control for electrically controlled fluid-operated presses comprising in combination an electric circuit, a manual switch for closing said circuit, a solenoid initially energized by closure of said manual switch, a limit switch adapted to be closed a predetermined time following energization of the solenoid, a relay whose circuit is completed upon the closing of said limit switch, a holding circuit for said relay which is completed upon closure of said relay, and a maintaining circuit for the solenoid which is completed upon the said closure of the relay, said holding circuit and maintaining circuit remaining closed after said manual switch has been opened.

5. In a control for electrically controlled fluid-operated presses, comprising in combination a manually closed circuit, a solenoid initially in said manually closed circuit, a limit switch which closes a predetermined time after energization of said solenoid, a relay, the circuit for which is completed by closure of the limit switch, a hold-

ing circuit for said relay completed by the said energization of the relay, and a maintaining circuit for said solenoid closed by the establishment of the relay circuit.

6. In a control for electrically controlled fluid-operated presses, comprising in combination a pair of manually operated switches, a solenoid, the circuit of said solenoid initially being established by closure of said manually operated switches, a limit switch adapted to be closed a predetermined time after the establishment of the solenoid circuit, a relay, the circuit for which is established by closure of the limit switch, a holding circuit for said relay separate from the solenoid circuit, said relay holding circuit being established by establishment of the relay circuit, and a maintaining circuit for the solenoid separate from the first-mentioned solenoid circuit,

said maintaining circuit being established by establishment of the relay circuit.
